UNITED STATES PATENT OFFICE.

CLYDE J. COLEMAN, OF ROCKAWAY, NEW JERSEY, ASSIGNOR TO CONRAD HUBERT, OF NEW YORK, N. Y.

ENGINE-STARTER.

No. 857,599.

Specification of Letters Patent.

Patented June 25, 1907.

Application filed July 16, 1904. Serial No. 216,912.

To all whom it may concern:

Be it known that I, CLYDE J. COLEMAN, a citizen of the United States, residing at Rockaway, in the county of Morris and State of New Jersey, have invented certain new and useful Improvements in Engine-Starters, of which the following is a specification, reference being had therein to the accompanying drawing, forming a part thereof.

10 My invention relates to starting means for engines not self-starting, such as explosion engines, and means embodying my invention are particularly adapted for use on engines of automobiles by reason of the frequent necessity in the use of automobiles for the performance of the starting operation.

15 My invention has for its objects simplicity of construction, durability, reliability in operation, and the realization of other advantages which will appear from the following specification.

20 My invention includes improved means whereby a power-storing device is connected with the engine to start the engine and 25 whereby the engine is connected to the power-storing device to store power therein at a reduced speed of the power-storing device relatively to the engine so as to minimize the load upon the engine during the power-storing 30 operation.

35 My invention also includes improved means for effecting the engagement and release of centrifugal engaging means whereby the engine is connected to the power-storing device upon the attainment of a predetermined speed of the engine and whereby an inoperative condition of the centrifugal means is effected by the power-storing device when the power-storing device is fully 40 charged.

45 My invention also includes various improvements in the construction and combination of parts generally applicable to power starting means and specifically combined with spring starting means.

50 I will now describe the construction embodying my invention illustrated in the accompanying drawings and will thereafter point out my invention in claims.

55 Figure 1 is a longitudinal vertical section of the starter. Fig. 2 is a transverse vertical section of the same taken on a plane indicated by the line 2-2, Fig. 1. Fig. 3 is a

transverse vertical section on a different plane indicated by the line 3-3, Fig. 1, also 55 looking to the left in Fig. 1. Fig. 4 is a detached front elevation of the clutch disk. Fig. 5 is a detached plan view of the clutch-dog releasing device. Fig. 6 is a detail section showing the detent for one of the 60 governor arms, taken on an oblique plane indicated by the line 6-6, Fig. 2. Fig. 7 is a face view of the clutch-dog releasing device. Fig. 8 is a diagrammatic view of the starting means and an explosion engine to which it is 65 connected and of portions of an automobile body.

The engine 1 illustrated in outline in Fig. 8 is an explosion engine of ordinary construction, which by reason of the fact that it is 70 non-starting or not self-starting, requires the application of a rotative force to its main shaft 5 to initiate the rotative movement thereof and to continue such movement until the engine is self-actuated. The direction of 75 rotation of the engine is indicated by the arrow 4. The rotative force is shown as applied through the sprocket-wheel 14 fixed on the engine shaft 5 and driven by a chain 12 running over this sprocket-wheel and also 80 running over the sprocket-wheel *r* of the starter, the last mentioned sprocket-wheel *r* being the engine-connected part of the starter.

The retractive power storing device of the 85 starter is shown as a pair of coiled or helical springs *a*, *a*, each of which is secured at its inner end to a fixed sleeve *a'* on the stationary shaft *c* of the starting means, and is secured at its outer end to a drum *d*, this drum 90 inclosing the springs and being carried at its rear end by a partly internally threaded hub *e'*, bearing at its unthreaded portion on the stationary shaft *c* and fitted to rotate thereon. The drum has at its front end a head *d'*, 95 also fitted to rotate on the shaft *c*. The shaft *c* is keyed in standards 8 and 9 of the starter frame, this frame also having a base-plate 7. This drum is hereinafter referred to as a part connected to the spring or power-storing device and as a spring-connected part and power-storing-device-connected part.

A lock-wheel *b* is fitted to rotate freely upon a starting and winding sleeve *f*, herein-after referred to as a starting and storing 105 part which is fitted to rotate freely upon the

starter shaft *c*. This lock-wheel *b* has square teeth which are engaged by the spring-controlled starting-pawl *b'* carried by the front drum-head *d'*, this pawl and toothed connection being hereinafter referred to as unidirectional engaging means; and these square teeth are of sufficient width to be also engaged at different portions of their width by a tooth *j* of a lock-arm 10, this lock-arm being pivoted to a lug 11 of the frame and actuated by a rod 16 shown as connected to an actuating pedal 17; this pedal being conveniently located in the body 20 of the automobile so that it may be readily actuated by the operator and depressed to unlock the lock-wheel *b* and permit the starter-springs to start the engine, and so that the pedal may be released to permit the helical springs 13, connected to the lock-arm 10 and the base-plate 7 of the starter frame, to return the lock-arm 10 to locking position, thereby elevating the pedal. The lock-arm is limited in its unlocking movement by the engagement of a notched stop-piece 18 thereon with a stop-pin 15, and constitutes with its toothed and connected part the locking device for the lock-wheel.

The starting and winding sleeve *f* has fixed thereon a starting ratchet-wheel *g* and a winding clutch-disk *h*. The sprocket-wheel *r*, over which runs the chain 12 connecting the starter with the engine shaft, is fitted loosely on this sleeve between the starting ratchet-wheel and the winding clutch-disk. This sprocket-wheel *r* carries starting-pawls, of which two *g', g'* are shown, these starting-pawls engaging the teeth of the starting ratchet-wheel *g* during the starting operation to transmit the rotation of the starting and winding sleeve *f* to the engine-connected sprocket-wheel *r*. When the engine is self-actuated these starting-pawls are carried forward and are drawn outward by centrifugal force, overcoming their light springs *g²*, *g²*, and moving them clear of the starting ratchet-wheel *g*, so that during the self-actuation of the engine they will be held by centrifugal force out of contact with the ratchet-wheel and will not rub over the teeth of the wheel, and the wear and noise which would otherwise result will thus be avoided. When, however, the engine slows down below a predetermined speed, the springs *g²* will move the pawls inward into contact with the teeth of the starting ratchet-wheel and they will be in position to engage the ratchet-wheel to receive the thrust of the starting springs and will be held in contact therewith by their locking engagement until released and thrown outward by the self-actuation of the engine. These starting pawls *g'* are therefore centrifugal pawls which are moved by centrifugal force out of engaging position. They and their ratchet-wheel are also unidirectional engaging means connecting the starting and

winding sleeve *f* with the engine-connected sprocket-wheel *r*, which engage and transmit the starting thrust from the spring-connected part to the engine-connected part.

The lock-wheel *b* carries planetary gears, of which three *i*, *i*, *i*, are shown, which mesh with the internal gear teeth of the spring drum head *b'*, these internal gear teeth being shown as formed upon a ring *d²* tightly fitting an overhanging part of the head. These planetary gears also mesh with a central pinion *f'* on the starting and winding sleeve *f* and shown as formed on an enlargement thereof. It will be noted that the lock-wheel *b*, which carries the planetary gears *i*, is fitted to rotate upon the starting and winding sleeve *f* between the pinion *f'* and the starting ratchet-wheel *g* and that it has a disk portion which fits loosely within the spring drum *d'* so as to inclose the gears, and has an annular portion on which the square lock-teeth are formed and which overhangs the starting ratchet-wheel *g* and its pawls *g'*, thus inclosing these parts and affording a very compact construction.

The parts above described perform the starting operation. This operation will now be described before describing the power-storing or winding mechanism and the operation whereby the springs are automatically wound so as to be ready to perform the starting operation.

The thrust of the starter-springs *a*, *a*, when wound, is exerted upon the spring-drum *d* in the direction in which the engine is to be rotated, and the lock-pawl *b'*, by its engagement with the lock-wheel *b*, prevents rotation of this spring-drum relatively to the lock-wheel *b* under the thrust of the starter-springs, while the lock-arm 10, by engagement of its tooth *j* with the lock-wheel *b*, prevents rotation of the lock-wheel *b* under the thrust of the starter-springs, and thus the starter is securely held with its springs wound ready to start the engine. When the pedal 17 is depressed by the operator, the lock-arm 10 is moved to unlock the lock-wheel *b*. When the lock-wheel is thus unlocked, the thrust of the starter-springs causes it to rotate with the spring-drum, and as the planetary gears are carried by the lock-wheel, these planetary gears revolve with the internal gear on the spring-drum *d* and impart rotation to the central pinion *f'* at the same rate of rotation as the spring-drum—the spring-drum with its internal gear, the lock-wheel with its planetary gears and the starting and winding sleeve *f* with its central pinion, rotating as a rotary unit and imparting the thrust of the starter-springs to the starting and winding sleeve. The starting ratchet-wheel *g* on the sleeve *f* imparts the rotative movement of the sleeve to the sprocket-wheel *r* through the starting-pawls *g'*, and therefore the sprocket-wheel *r* is rotated at 13.

the same rate of rotation as the spring-drum and the power of the starter-springs is directly applied to the work of starting the engine. The propulsive force of the starter-springs causes the rotation of the engine shaft until the engine becomes self-actuating with greater rotative force than is applied to it by the starter-springs, but when this condition is attained the starting-pawl g' will 5 be advanced and moved outward by centrifugal force, as above described, so that their continued movement under the operation of the engine will be altogether clear of contact with the starting ratchet-wheel g . 10 To prevent unwinding of the springs beyond their natural or normal set or shape, which would tend to wind them up in an opposite direction and might break springs of considerable strength, I provide a reciprocating 15 stop-pin k fitted to move longitudinally in a lug 19 of the starter-frame and in the standard 9 thereof, and actuated by a lever m as hereinafter explained, so that it will be projected rearwardly into the path of the head 20 b' of the pivot-pin of the lock-pawl b' and will stop the spring-drum by contact with such head before the springs have become unwound beyond their normal set. The automatic operation of this reciprocating stop- 25 pin is required so that it will not be projected into operative position until after the commencement of the final revolution which would be terminated by contact with this stop-pin should the springs become so far 30 unwound.

Ordinarily the release of the pedal will occur before the exhaustion of the starter-springs, but should it be delayed beyond the point of exhaustion of the starter-springs, no 35 injury could result to the mechanism by reason of the construction above described. The strength and capacity of the starter-spring would usually be such as to allow an ample margin over the maximum work required to start the engine.

The winding clutch-disk h is provided with clutch-dogs, of which two o, o' are shown. These clutch-dogs are normally held in their extreme outer positions, shown in Fig. 2, by 40 light springs o', o' , as well as by centrifugal force. Centrifugal or governor-arms are also provided, carried by the sprocket-wheel r and pivotally mounted thereon, two of these arms p, p' , being shown, each governor- 45 arm having a weighted end and a toothed end and the governor-arms being connected by helical extensible springs p', p' , tending to hold the arms in the position shown in Fig. 2, with their toothed ends clear of the path of 50 the clutch-dogs o, o' . Centrifugal force will tend to move the weighted ends of the governor-arms outward and their toothed ends inward. For the purpose of restraining the movement of these governor-arms I provide 55 spring-detents s therein which normally

enter depressions in the face of the sprocket-wheel r (see Fig. 6), affording a resistance superadded to that of the governor-springs p' and holding the governor-arms until a centrifugal force is developed which will move 60 them quickly outward and will thereby cause a quick inward movement of their toothed ends and a positive engagement with the clutch-dogs o, o' of the winding clutch-disk h . This movement will not occur until a predetermined speed of the engine, usually its full speed, has been attained, so that the work of winding the starter-springs will not have to be performed by the engine until it is fully capable of performing such operation in addition to its ordinary work. The movement of the governor-arms is limited by ordinary fixed pins r' entering slots in the face of the 70 sprocket-wheel r .

When the winding clutch-disk h is actuated 80 by the sprocket-wheel r , the starting and winding sleeve f and the central pinion f' thereon will be rotated and the planetary gears i will be rotated and will transmit rotation to the internal gear d' of the spring-drum d in the opposite direction and at reduced speed, rotating the spring-drum and winding the starter-springs a . The reduced speed of the spring-drum during this winding operation diminishes the load upon the engine during the winding operation, and it is to be especially noted that this advantage of leverage to the engine during the winding operation is not present during the starting operation, as during that operation, as above described, the spring-drum and starting and winding sleeve rotate at the same rate of speed.

I provide for automatically discontinuing the winding or power-storing operation when the springs have been fully wound, by disengaging the clutch-dogs o of the winding clutch disk h from the toothed ends of the governor-arms p . This is accomplished by a releasing plate t loosely mounted upon the 100 starter-shaft c near the front end of the shaft so as to bear against the back of the front standard 9 when in inactive position, as shown. This releasing plate t is provided with overhanging ends t', t' , the inner arc-shaped faces of which are adapted, when the releasing plate is moved rearward, to engage 105 forward projections on the clutch-dogs o (see Fig. 4) and thereby to move the clutch-dogs inward clear of the toothed ends of the governor-arms p . The releasing plate t is yieldingly held against limited rotative movement by spring-pins u, u' , sliding in lugs u', u' (see Fig. 7), these lugs projecting rearward from the front standard 9 and having inclined 110 faces co-acting with the inclined faces on the ends of the releasing plate t (see Figs. 5 and 7) to assist in moving the releasing plate 115 rearward away from the front standard 9 and into position to engage the clutch-dogs. The 120

125

spring-pins *u* press the releasing plate *t* against a stop-pin *u*².

The control of the releasing plate *t* from the starter springs *a* is accomplished by means of a slide-rod *e* seated in a key-way in the starter-shaft *c* and shaped at its rear end to engage the internal threads of the rear hub *e'* of the spring-drum so that it will be moved forward as the starter-springs unwind and will be moved rearward as the starter-springs are wound up.

The slide-rod *e* in its extreme forward position, as shown, comes in contact with and pushes forward the upper end of the stop-pin lever *m*, thereby causing the reciprocating stop-pin *k* to be projected into the position shown, in which it will come in contact with the head *b*² of the pivot-pin of the lock-pawl *b'* so as to arrest the movement of the spring-drum and starter-springs beyond the normal set of the starter-springs, thereby preventing the possibility of breaking the springs. The stop-pin *k* is withdrawn upon the rearward movement of the slide-rod *e* by the spring *m'* bearing against the stop-pin lever *m*, so as not to interfere with the rotation of the spring-drum in other than the final revolution thereof. The slide-rod *e*, as it approaches its extreme rearward position or the position corresponding to the wound condition of the starter-springs, causes the releasing plate *t* to be moved rearward so that its overhanging ends *t'*, *t'*, will engage with and move inward the clutch-dogs *o*, *o*. This actuation of the releasing plate is accomplished by means of an actuating spring-pin *v* loosely fitted in the releasing plate in position to be engaged and actuated by projections *v'*, *v*², on the slide-rod *e*. These parts are shown with the releasing plate in forward and disengaged position, and with the actuating spring-pin *v* pressed inward by the projection *v*² of the slide-rod *e*. As the slide-rod *e* is moved rearward during the winding of the springs, the actuating spring-pin *v* is projected in front of the projection *v*² and thereafter contacts with the rear face of the front projection *v'*, and the engagement of these faces projects the releasing plate rearward into engaging position, as soon as the force developed is sufficient to overcome the detent spring-pin *w*. The rearward movement of the releasing plate brings the arc-shaped faces of the releasing plate into engagement with the clutch-dogs *o*, pressing the clutch-dogs inward and disengaging them from the toothed ends of the governor-arms *p*. The successive positions of one of the clutch-dogs at and after contact with an arc-shaped face of the releasing plate are shown in broken lines in Fig. 7. The function of the detent spring-pin *w* is to oppose a resistance which will retain the releasing plate *t* in forward and disengaged position until a force is developed which will move it quickly into engaging po-

sition, thus assuring an effective movement to release the clutch-dogs. The spring-pins *u* cushion the impact of the clutch-dogs against the overhanging projections *t'* of the releasing plate, and also by virtue of their inclined abutment against or engagement with the ends of the releasing plate, assist the movement of the releasing plate into engaging position. The pushing inward or disengagement of the clutch-dogs from the toothed ends of the governor-arms will disconnect the winding clutch-disk *h* from the sprocket-wheel *r* and terminate the winding or power-storing operation. The starter-springs having been fully wound will be ready to perform a starting operation, and as they perform the starting operation the springs will unwind and thereby the slide-rod *e* will be moved forward, and when the front face of the projection *v*² of the slide-rod *e* comes in contact with the actuating spring-pin *v*, the releasing plate will be moved forward clear of the projections of the clutch-dogs *o* and the clutch-dogs will be restored to their normal positions shown, ready to be engaged by the toothed ends of the governor-arms when the engine is self-actuated at the predetermined or full speed. This disengagement of the releasing plate from the clutch-dogs will occur after a comparatively small unwinding movement of the starter-springs, so that if the engine is quickly started with the employment of much less than the full power of the springs, and the pedal 17 is promptly released and the lock-wheel *b* locked to prevent further unwinding of the starter-springs, the clutch-dogs will nevertheless be released by this comparatively small unwinding movement and will be restored to their normal positions, and the centrifugal-clutch will be ready to rewind the springs upon the development of sufficient centrifugal force from the rotation of the engine to cause the toothed ends of the governor-arms to engage the clutch-dogs. The consequence of this construction is that the starter-springs, although non-automatically controlled at the lock-plate *b*, are at all times sufficiently wound to start the engine, except during short periods between a long unwinding movement and its following winding movement.

It is obvious that various modifications may be made in the construction shown and above particularly described within the principle and scope of my invention.

What I claim and desire to secure by Letters Patent is:—

1. An engine-starter comprising a power-storing device, a lock-wheel and means for unlocking the same, a rotating sleeve, speed-reducing gearing fulcrumed on the lock-wheel and connecting the sleeve and power-storing device, means for starting the engine by the power-storing device through rota-

tion of the lock-wheel and without relative movement of the parts of the gearing, and means for actuating the power-storing device from the engine through actuation of the reducing gearing.

2. An engine-starter comprising a power-storing device, a lock-wheel and means for unlocking the same, a rotating sleeve, speed-reducing gearing fulcrumed on the lock-wheel and connecting the sleeve and power-storing device, means for starting the engine by the power-storing device through rotation of the lock-wheel and without relative movement of the parts of the gearing, and centrifugally-operated means movable by centrifugal force into engaging position to connect the engine and sleeve and actuate the power-storing device from the engine through the sleeve and reducing gearing.

20 3. An engine-starter comprising a starter-spring, a gear connected thereto, a lock-wheel and means for unlocking the same, a rotating sleeve provided with gear teeth, planetary gearing carried by the lock-wheel and meshing with said gear and sleeve, means for starting the engine by the starter-spring through rotation of the lock-wheel and without relative movement of the parts of the gearing, and means for winding the spring from the engine through the sleeve and planetary gearing.

25 4. An engine-starter comprising a starter-spring, a gear connected thereto, a lock-wheel and means for unlocking the same, a rotating sleeve provided with gear teeth, planetary gearing carried by the lock-wheel and meshing with said gear and sleeve, means for starting the engine by the starter-spring through rotation of the lock-wheel and without relative movement of the parts of the gearing, and centrifugally-operated means movable by centrifugal force into engaging position to connect the engine and sleeve and wind the spring from the engine through the sleeve and gearing.

30 5. An engine-starter comprising a power-storing device, a rotating power-transmitting member connected thereto, a rotating part connected with the engine, means engageable only in one direction of movement for connecting such power-transmitting member with the engine-connected part, a governor-arm carried by the engine-connected part, a clutch-dog carried by the power-transmitting member and located in position to be engaged by the governor-arm upon the attainment of a predetermined speed of the engine-connected part, and releasing means for the clutch-dog controlled by the power-storing device.

35 6. An engine-starter comprising a power-storing device, a rotating part connected with the engine, means engageable only in one direction of movement for connecting the power-storing device and engine-connected part, a governor-arm carried by the engine

connected part, a rotating clutch-dog-carrier connected to the power-storing device and a clutch-dog carried thereby in position to be engaged by the governor-arm upon the attainment of a predetermined speed of the engine-connected part, and releasing means for the clutch-dog controlled by the power-storing device.

7. An engine-starter comprising a power-storing device, a gear connected thereto, a rotating engine-connected part, a lock-wheel and means for unlocking the same, the said gear and the engine-connected part and the lock-wheel having a common axis of rotation, means for connecting the power-storing-device-connected part with the lock-wheel to start an engine by the power-storing device, and means including speed-reducing gearing fulcrumed on the lock-wheel for connecting the engine-connected part with said gear to store power therein.

8. An engine-starter comprising a power-storing device, a rotating part connected with the engine, a lock-wheel and means for unlocking the same, the engine-connected part and the lock-wheel having a common axis of rotation, means for connecting the power-storing device with the engine-connected part to start an engine by the power-storing device, and centrifugal means including speed-reducing gearing fulcrumed on the lock-wheel for connecting the engine-connected part with the power-storing device to store power therein.

9. An engine-starter comprising a power-storing device, a rotary clutch-dog carrier connected therewith, a rotating part operatively connected with the engine and centrifugal connecting means carried thereby, the clutch-dog carrier and the engine-connected part having a common axis of rotation, means engageable only in one direction of movement for connecting the power-storing device with the engine-connected part to start an engine, a clutch-dog carried by the clutch-dog carrier and located in position to co-act with the centrifugal connecting means upon the attainment of a predetermined speed of the engine-connected part, releasing means for the clutch-dog, and means controlled by the power-storing device and controlling the releasing means.

10. An engine-starter comprising a power-storing device, a gear connected thereto, a rotating power-transmitting member provided with gear teeth, a lock-wheel connected to the power-storing device by means engageable only in one direction of movement, a planetary pinion carried by the lock-wheel and engaging said gear and power-transmitting member, a locking device for the lock-wheel, and means for connecting the power-transmitting member with an engine to start the engine by rotation of the gear in the direction in which the lock-wheel

and gear are engageable and for connecting the power-transmitting member with the engine to store power in the power-storing device by rotation of the gear in the opposite direction.

11. An engine-starter comprising a power-storing device, a rotating part operatively connected with the engine, means for connecting the power-storing device with the engine-connected part to start an engine by the power-storing device, centrifugal connecting means carried by the engine-connected part, a rotating clutch-dog carrier connected to the power-storing device, a clutch-dog carried thereby and normally located in position to co-act with the centrifugal connecting means upon the attainment of a predetermined speed of the engine-connected part, a movable releasing plate engageable with the clutch-dog to move the clutch-dog out of such co-active position, and means controlled by the power-storing device for moving such releasing plate into such operative position.

12. An engine-starter comprising a power-storing device, a rotating part operatively connected with the engine, means for connecting the power-storing device with the engine-connected part to start an engine by the power-storing device, centrifugal connecting means carried by the engine-connected part, a rotating clutch-dog carrier connected to the power-storing device, a clutch-dog carried thereby and normally located in position to co-act with the centrifugal connecting means upon the attainment of a predetermined speed of the engine-connected part, a movable releasing plate engageable with the clutch-dog to move the clutch-dog out of such co-active position, means controlled by the power-storing device for moving such releasing plate into such operative position, and yielding means controlling the releasing plate.

13. An engine-starter comprising a power-storing device, a rotating part operatively connected with the engine, means for connecting the power-storing device with the engine-connected part to start an engine by the power-storing device, centrifugal connecting means carried by the engine-connected part, a rotating clutch-dog carrier connected to the power-storing device, a clutch-dog carried thereby and normally located in position to co-act with the centrifugal connecting means upon the attainment of a predetermined speed of the engine-connected part, a movable releasing plate engageable with the clutch-dog to move the clutch-dog out of such co-active position, means controlled by the power-storing device for moving such releasing plate into such operative position, and yielding means controlling the releasing plate, the yielding means and releasing plate having an inclined abutment tending

to advance the releasing plate into further engagement with the clutch-dog.

14. An engine-starter comprising a starter-spring, a gear connected thereto, a rotating power-transmitting member provided with gear teeth, a lock-wheel connected with said gear by means engageable only in one direction of movement, a planetary gear carried by the lock-wheel and engaging teeth on the gear and on the power-transmitting member, a locking device for the lock-wheel, means for connecting the power-transmitting member with an engine to start the engine by rotation of the gear in the direction in which the lock-wheel and gear are engaged and for connecting the power-transmitting member with the engine to wind the spring by rotation of the gear in the opposite direction, and a stop for the gear controlled by the movement of such member.

15. An engine-starter comprising a power-storing device, a rotating power-transmitting member, a rotating part operatively connected with the engine, means engageable only in one direction of movement for connecting the power-storing device with the power-transmitting member, and directional engaging means for connecting the power-transmitting member with the engine-connected part to start the engine by the power-storing device, a centrifugal-arm carried by the engine-connected part, a clutch-disk carried by the power-transmitting member and a clutch-dog on such disk and located in position to co-act with the centrifugal-arm upon the attainment of a predetermined speed of the engine-connected part, and motion-transmitting means for connecting the power-transmitting member with the power-storing device during the centrifugal-clutch-actuated movement thereof.

16. An engine-starter comprising a power-storing device, a rotating part operatively connected with the engine, means engageable only in one direction of movement for connecting the power-storing device with the engine-connected part to start the engine, a centrifugal-arm carried by the engine-connected part, a clutch-dog carrier connected to the power-storing device, a clutch-dog carried thereby and normally located in position to co-act with the centrifugal-arm upon the attainment of a predetermined speed of the engine-connected part, a slide-rod controlled by the power-storing device, a movable releasing plate engageable with the clutch-dog to move the clutch-dog out of said co-active position, and an actuating spring-pin carried by the releasing plate, the slide-rod having abutments located in position to co-act with such spring-pin.

17. An engine-starter comprising a power-storing device, a rotating part operatively connected with the engine, means engageable only in one direction of movement for con-

necting the power-storing device with the engine-connected part to start the engine by the power-storing device, a centrifugal-arm carried by the engine-connected part, a clutch-dog carrier connected to the power-storing device, a clutch-dog carried thereby and normally located in position to co-act with the centrifugal-arm upon the attainment of a predetermined speed of the engine-connected

part, a slide-rod controlled by the power-storing device, a movable releasing plate engageable with the clutch-dog to move the clutch-dog out of said co-active position, an actuating spring-pin carried by the releasing plate, the slide-rod having abutments located in position to co-act with such spring-pin, and a detent for restraining the movement of the releasing plate.

18. An engine-starter comprising a power-storing device, a rotating engine-connected part, means engageable only in one direction of movement for connecting the power-storing device and engine-connected part, centrifugal means for connecting the engine-connected part with the power-storing device to store power in the power-storing device, a thrust device controlling the centrifugal means, and connections between the thrust device and the power-storing device comprising helically engaging parts, whereby an inoperative condition of the centrifugal means is effected by the power-storing device

when the power - storing device is fully charged.

19. In an engine-starter, the combination, 35 of a means for storing energy, a reversible gearing connected thereto, a clutch connecting the gearing to the engine, and devices for controlling the clutch and gearing to cause the gearing to transmit to or from the means 40 for storing energy.

20. In an engine-starter, the combination of means for storing energy, a reversible gearing connected thereto, a clutch joining the gearing to the engine, and devices automatically actuated from said means for storing energy to adjust the clutch and gearing and cause them to transmit to the means for storing energy. 45

21. In an engine-starter, the combination 50 of a means for storing energy, a rotary shaft, means connecting it to the engine, a gear in connection with said means for storing energy, a gear in connection with the shaft, an independently-rotatable member, a gear carried thereby, and means for arresting the movement of said independently-rotatable member at will.

In testimony whereof I have affixed my signature in presence of two witnesses.

CLYDE J. COLEMAN.

Witnesses:

HENRY D. WILLIAMS,
HERBERT H. GIBBS.
